E. H. RIPLEY, OF NORTH CHELMSFORD, MASSACHUSETTS.

Letters Patent No. 79,006, dated June 16, 1868.

IMPROVEMENT IN MACHINES FOR PLANING MOULDINGS.

The Schedule referred to in these Letters Patent and making part of the same.

TO ALL WHOM IT MAY CONCERN:

Be it known that I, E. H. RIPLEY, of North Chelmsford, in the county of Middlesex, and State of Massachusetts, have invented a new and useful Improvement in Moulding-Machine; and I do hereby declare that the following is a full, clear, and exact description thereof, which will enable those skilled in the art to make and use the same, reference being had to the accompanying drawings, forming part of this specification, in which—

Figure 1 is a side view of my improved machine, partly in section, to show the construction.

Figure 2 is a detail view of the eccentric rocking-plate or frame.

Figure 3 is a top view of my improved machine, part broken away, to show the construction.

Figure 4 is a vertical cross-section of the same, taken through the line $x\ x$, fig. 3.

Similar letters of reference indicate corresponding parts.

My invention has for its object to furnish a neat, simple, and effective machine for forming mouldings, which shall be so constructed and arranged that by very simple adjustments the same cutter may be used for cutting mouldings of many different designs.

And it consists in the construction and combination of the various parts, as hereinafter more fully described.

A are the end-frames of the machine.

B is the horizontal frame, the ends of which are attached to the middle parts of the end-frames A.

C is the top plate or table of the machine.

D is the cone-pulley, by means of which motion is communicated to the machine, and which revolves upon a journal attached to the outer side of one of the end-frames A.

E is a small gear-wheel, attached to or connected with the cone-pulley D in such a way as to be carried with said cone-pulley in its revolution.

F is a gear-wheel attached to the end of the shaft G, and the teeth of which mesh into the teeth of the gear-wheel E.

The shaft G revolves in bearings attached to the frames A and B, and to its inner end is attached a gear-wheel, H, the teeth of which mesh into the teeth of the gear-wheel I, attached to the cam-shaft J.

Upon the end of the shaft J is secured a segmental gear-wheel, K, the teeth of which mesh into the teeth of the gear-wheel L, attached to the shaft M, from the pulley N of which motion is communicated to the feed-shaft.

To the inner end of the shaft J are attached two cams, O and P, which operate the levers Q and R.

The lever Q is pivoted to a standard, S, attached to the frame B, and one of its ends rests upon the cam O, so as to be operated by the movement of said cam.

The outer end of the lever Q is curved, as shown in fig. 1, so that the cam P may revolve without touching the lever Q.

From the extreme end of the lever Q is suspended a weight, T, to bring the lever Q back to its place when released from the cam O.

To the inner end of the lever Q is pivoted the lower end of the connecting-rod U, the upper end of which is pivoted to the side or edge of the pivoted frame or plate V, or to an arm projecting from said plate or frame.

The rod U, I prefer to make in two parts, having a right and left screw-thread cut upon their adjacent ends, which enter the opposite ends of the hand-nut W, so that by turning the said hand-nut the said ends of the said parts may be moved closer together or farther apart, to adjust the length of the said rod U as may be required.

The lever R is suspended from and pivoted to the head of the screw-bolt X, which passes up through a hole in the frame B, and has a hand-nut, Y, screwed upon its upper end, so that it may be adjusted as required.

To one end of the lever R is pivoted the lower end of the rod Z, which passes up through a guide into such a position that its upper end may rest against the cam P, so that the lever R may be operated by the movement of the said cam P.

To the other end of the lever R is pivoted a short rod, A', having a socket formed in its upper end, and which is held in a vertical position, and made to move up and down in a vertical line, by the cross-bar B',

through which it passes, and which is kept in proper position by the guide-pins C', which pass through its ends, and which are attached to the frame B, as shown in fig. 4.

D' is a vertical shaft, the lower end of which enters and works in the socket A'.

The vertical shaft D' passes up through the collar E', and to its upper end is attached the plate F'.

The collar E' is pivoted to the plate or frame V by two set-screws, G', which pass longitudinally through the middle part of the frame or plate V, in the same vertical plane with the pivoting-points of said frame, but at a higher level than said pivoting-points, so that the frame may rock upon the said collar.

The ends of the frame or plate V are curved downwards, as shown in figs. 2 and 4, and are pivoted to arms H', attached to the under side of the table C, so that, as the said plate or frame V is rocked upon its pivoting-points, the upper end of the vertical shaft D' may be moved forward or back.

To the rear edge of the plate F' is pivoted or hinged the lower edge of the plate or frame I', the upper edge of which is rigidly attached to the rear edge of the feed-box J'.

To the forward edge of the plate F' is pivoted the lower end of a curved guide-rod, K', which passes up through a hole in the forward part of the feed-box J', or in a guide-block, L', rigidly attached to the forward edge of said feed-box.

This construction allows the feed-box to be tilted or adjusted at any desired angle with the plate F'.

When adjusted, the feed-box J' is secured in place by the set-screw M', the forward end of which presses against the guide-rod K', as shown in figs. 1 and 3.

N' are the lower feed-rollers, which are placed beneath the feed-box J', in such positions that their upper sides may project through slots or openings in said feed-box, to take hold of the material to be fed forward to the cutter.

The feed-rollers N' are toothed spirally, as shown in figs. 1 and 3, so that they may always hold the material close up against the guide-plate j' of the feed-box J'.

The journals of the feed-rollers N' revolve in bearings attached to the under side of the feed-box J', and to their projecting ends are attached the gear-wheels O', the teeth of which mesh into the teeth of the gear-wheel P', attached to the end of the feed-shaft Q', to which motion is communicated by a band passing around the pulley R', attached to said shaft, and around the pulley N, attached to the shaft M.

The feed-shaft Q' has a universal joint, S', formed upon it, so that the gear-wheels O' and P' may always work freely, at whatever angle the feed-box J' may be adjusted.

T' are the upper feed-rollers, the journals of which are adjustably secured to the guide-plate j' of the feed-box J', or to standards attached to said feed-box, as shown in fig. 4, so that they may be raised or lowered according to the thickness of the material to be operated upon.

U' is a downwardly-projecting arm, attached to the lower part of the collar E' below the pivoted or rocking-plate or frame V, the lower end of which is slotted, to receive the end of the arm V', adjustably secured to the vertical shaft D' by a set-screw, as shown in fig. 1.

This construction allows the feed-box J' to be set at an angle with the cutter, so that the said cutter may strike the material obliquely, and thus cut a wider groove than would be possible if the cutter struck the material at right angles to its length.

W' is the cutter, which is attached to the cutter-head in the ordinary manner.

X' is the cutter-head shaft, to which motion is given in the ordinary manner, by a band passing around a pulley, Y', attached to said shaft, or by any other convenient means.

I claim as new, and desire to secure by Letters Patent—

1. Pivoting or hinging the feed-box J' to the plate F' attached to the upper end of the vertical shaft D', substantially as herein shown and described and for the purpose set forth.

2. The eccentric-plate or frame V, constructed substantially as herein shown and described, in combination with the vertical shaft D', as and for the purpose set forth.

3. The combination of the adjustable connecting-rod U, and weighted or balanced lever Q, with the cam O and pivoted eccentric-plate or frame V, substantially as herein shown and described and for the purpose set forth.

4. The combination and arrangement of the slotted lever R, centrally pivoted to the vertically-adjustable support X Y, the rod Z and step A', with relation to the cam P and vertical shaft D', all constructed and arranged to operate in the manner and for the purpose, substantially as herein shown and described.

5. The combination of the adjustable arm V' and slotted rigid arm U' with the vertical shaft D' and pivoted collar E', through which said shaft passes, substantially as herein shown and described, and for the purpose set forth.

E. H. RIPLEY.
